ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

FRICTION DEVICE FOR YARN SPOOLS.

Application filed February 29, 1924. Serial No. 696,073.

This invention relates to looms of the type in which the tuft yarn is wound upon spools which are mounted upon separate tube frames. These frames are removed one at 5 a time from the transporting chains and are presented to the warps by frame holders especially provided for that purpose. It has been customary to provide a separate friction device for each yarn spool but it 10 has been found that these friction devices vary widely in their holding effect and that it is not practical to keep the friction uniform on different spools. Nevertheless, it is extremely desirable that the resistance to 15 rotation of the spools, as the yarn is drawn therefrom, shall be maintained substantially uniform.

It is the general object of my invention to provide a substantially uniform tension 20 for successive yarn spools as the tuft yarn is drawn therefrom. In the preferred form, normally operative friction devices are provided which hold the spools from rotation during the transportation thereof. Additional or supplementary friction devices are also provided for each yarn spool, which latter devices are brought into uniform operation as the tube frame is received in the frame holders. At the same time the normally operative tension devices are preferably rendered inoperative.

My invention further relates to arrangements and combinations of parts which will be hereinafter described and more particularly pointed out in the appended claims.

A preferred form of the invention is shown in the drawings, in which—

Fig. 1 is a front elevation of a portion of a yarn spool and a supporting tube frame; the head of the spool being shown in section;

Fig. 2 is an end elevation of the parts shown in Fig. 1;

Fig. 3 is a front elevation, partly in section, showing the parts seen in Fig. 1, together with a frame holder supporting the frame;

Fig. 4 is a side elevation of the mechanism shown in Fig. 3;

Fig. 5 is a detail sectional elevation taken along the line 5—5 in Fig. 4, and

Fig. 6 is a sectional plan view taken along the line 6—6 in Fig. 3.

Referring to the drawings, I have shown a tube frame 10 of a usual construction, on

which a plurality of yarn tubes 11 are 55 mounted in closely parallel relation. A yarn spool 12 is provided with a stud or bearing 13 which is rotatable in a bearing plate 14 fixed to the end of the tube frame 10. An outer plate plate 15 is also provided by which the tube frame may be attached to a transporting chain, not shown.

The spool 12 is preferably provided with a pressed metal head 16 which is normally engaged by a friction pad 17 mounted upon a flat spring 18 secured to the upper surface of the tube frame 10. The parts thus far described are or may be of the usual construction, with the exception that the spring 18 is preferably provided at its free 70 end with lateral projections 20 (Fig. 2) for a purpose to be described.

My invention relates particularly to the provision of a second friction device for each spool, herein shown as comprising a 75 friction pad 21 (Fig. 1) secured to an arm or plate 22 which is pivoted at 23 upon a bearing support 24. This support is held in position by folding the outer ends of the support snugly around the plates 14 and 15, 80 as indicated in Fig. 6.

Upward movement of the support is prevented by the outward curve of the plate 15, just above the support, and downward movement of the support is prevented by 85 providing inwardly projecting lugs 25 which engage shoulders on the plate 14. The friction arm 22 normally swings freely upon its pivot 23, without causing engagement of the pad 21 with the spool head 16.

A frame holder 26 of the usual type is provided for detaching the tube frame from its transporting chain and for supporting the tube frame and presenting the yarn tubes between the warp threads. While this 95 yarn holder is, as stated, of the usual type, it has two additional and novel features.

In the first place, cam-like projections 27 extend inward from the holder 26 on each side of the plates 14 and 15 and engage the lateral projections 20 of the spring 18 as the tube frame is detached. By such engagement, the spring 18 is depressed, separating its friction plate 17 from the spool head 16.

The frame holder 26 is also provided with a cylindrical portion 28, within which is mounted a plunger 29 yieldingly pressed to-

ward the spool head by a spring 30, the tension of which may be adjusted by a screw 31. One of these spring plungers is provided at each side of the holder 26 in position to engage both lateral projections of the pivoted friction arm or plate 22. With this construction the operation of my improved friction device is as follows:—

As the holder is moved laterally to approach and release the tube frame, the cam plate 27 engages the projections 20 and depresses the regular friction spring 18, thus releasing the usual friction upon the spool 12. At the same time, the plungers 29 engage 15 the pivoted plate 22 and force the friction pad 21 against the spool head 16. As the plungers 29 are mounted upon the holder 26, the same plungers apply the friction pressure to each of the successive spools and the 20 amount of friction is thus maintained substantially constant. As the same time, the usual friction spring 18 is permitted to operate during the transportation of the tube frame, when the exact amount of friction 25 is immaterial.

While I have shown and described only one spool end and only one set of parts of my improved mechanism, it will be understood that the parts herein shown and described are substantially duplicated at the 30 opposite end of the tube frame.

Having thus described my invention and the advantages thereof, I do not wish to be limited to the details herein disclosed otherwise than as set forth in the claims but what I do claim is:—

1. In a loom, a yarn spool, a tube frame on which said spool is rotatably mounted, a frame holder, means to apply friction to said spool when said tube frame is removed from said frame holder, additional means to apply friction to said spool when said tube frame is supported in said frame holder, and means to render said first fric- 40

tion means inoperative and to simultaneously render said second friction means operative when a tube frame is received in said frame holder. 45

2. In a loom, a plurality of yarn spools, a regular friction device for each spool, an additional friction device, and means to render said regular friction device inoperative and said additional frictional device substantially uniformly operative for each spool, as each spool is presented in yarn delivering position. 50

3. In a loom, a tube frame, a yarn spool mounted thereon, a friction device on said tube frame for said yarn spool, a second friction device for each yarn spool, a holder for said tube frame, and means on said holder to render said first friction device inoperative and said second friction device substantially uniformly operative upon the 60 positioning of said tube frame in said holder. 65

4. In a loom, a tube frame, a yarn spool mounted thereon, separate means to apply friction to each spool when removed from yarn delivering position, yielding means to apply substantially uniform friction to all 70 of said spools when in delivering position, and means to render said separate means inoperative when said yielding means is rendered operative. 70

5. In a loom, a tube frame, bearing brackets thereon, a yarn spool mounted in said brackets, a friction pad, springs connecting said pad to one of said brackets, said bracket having a central opening therein, a frame holder, and a spring-actuated plunger mounted in said frame holder and projecting through said opening to engage said pad and to apply friction to said spool when said tube frame is supported in said holder. 75

In testimony whereof I have hereunto affixed my signature. 85
